[57] **CLAIM**

The ornamental design for a tool handle cover, as shown and described.

DESCRIPTION

FIG. 1 is a left side perspective view of a tool handle cover showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a front view thereof, wherein the broken line showing of the tool head is for illustrative purposes only and forms no part of the claimed design; and,
FIG. 9 is a front view thereof, wherein the broken line showing of the tool head is for illustrative purposes only and forms no part of the claimed design.
